UNITED STATES PATENT OFFICE.

ROBERT L. OSBORNE, OF MOUNT CLEMENS, MICHIGAN, ASSIGNOR TO DONGAN ELECTRIC MANUFACTURING CO., OF DETROIT, MICHIGAN, A CORPORATION OF MICHIGAN.

TRANSFORMER.

Application filed July 7, 1922. Serial No. 573,307.

This invention relates to transformers for electric current, more particularly for current of a radio frequency type, and the object is to provide a transformer for use in the receiving circuits of radiophones in which eddy currents are practically avoided and to reduce what is termed the "static effect". Further, it is the object to provide a transformer adapted for use in radio receiving circuits as a "tuning" element whereby the receiving system is tuned by varying the inductance rather than by variation in capacity as has heretofore been the practice.

Previously, transformers have been used in receiving circuits which are made up of a laminated iron core but the use of such previous transformers has induced or produced a distortion of the wave form of the secondary circuit which results in a blurring of the sound wave emanating from the receiver. This blurring is often attributed to static effects which are multiplied by the usual form of transformer and this invention seeks to provide a transformer for current of radio frequency type in which the undesirable features of the usual laminated iron core transformer above mentioned are avoided and produces a secondary current whose wave form is not distorted through influence of eddy currents in the transformer. I have found by providing an iron core for the transformer, which is made up of strips of extreme thinness or of particles of iron, eddy currents are practically eliminated and further have found that by varying the position of the core relative to the primary and secondary coils the system may be tuned with far greater ease and excellence of results than with previous known types of transformers. The various objects and several novel features of my invention are hereinafter more fully described and claimed, and the preferred form of construction of a transformer embodying my invention is shown in the accompanying drawing in which—

Fig. 1 is a longitudinal section of a transformer embodying my invention.

Fig. 2 is a section taken on line 2—2 of Fig. 1.

Fig. 3 is a diagram showing the usual radiophone receiver circuit with my transformer positioned therein between the first and second lamps.

Fig. 4 is a section showing an alternative form of core for the transformer.

Preferably the transformer is made substantially as shown in Fig. 1 and consists of a case 1 of non-magnetic material apertured at one end for a rod 2 preferably of hard rubber or other non-magnetic material. The case may be made of hard rubber or fiber or the like and is further provided with a cap 3 for the end thereof, which cap may conveniently carry a cylindrical or tubular extension 4. On this extension is wound the secondary coil 5 which is in the form of two coils 5, 5 each wound in a groove provided therefor. The primary coil 6 is wound in a groove thereon, between the two secondary coils and a cover 7 of insulating material may be placed on the outside of the coils. The cap may be secured in position by a pair of screws 8, 8 and there are two terminals 9 and 10 for the secondary coil and two terminals 11 and 12 for the primary coil as will be understood from Fig. 2. These terminals may provide binding posts extending outward through the cap and provided with the nuts 13 to attach the circuit wires thereto. A core for this coil is indicated at 14 and is formed of a multitude of very fine strips of soft metal held in a case or shell 15 of insulating or non-magnetic material which is tubular in form and provided with a closure 16 at the forward end. The rod 2 is preferably integral with the shell 15 providing a closure for the opposite end. This rod 2 rides in the bearing 18 provided in the end of the case 1 and a spring-pressed ball 20 is provided at the end of the bearing and engages the rod 2. The core may be moved into or out of the shell or coil manually and the ball 20 holds the core in its set position due to its engagement with the rod 2. As is well understood, the inductance is increased as the metal within the influence of the coil is increased and decreased by withdrawing the metal from the coil.

An alternative form of construction is shown in Fig. 4 in which the iron of the core is in the form of very fine particles of iron held in the tube 15a of non-magnetic material and secured therein by an end plug 105 and rod as in the form of core shown in Fig. 1. In both these cores the iron is in a very finely divided form so that there is

very little iron in any one mass thus practically eliminating eddy currents which occur when the iron is in larger masses, the tendency of which is to distort the secondary 5 wave form.

The structure is simple and inexpensive in character and the core is readily adjusted in position whereby the best result may be secured in the receiver circuit. The receiver 10 circuit is not material as to its exact form and arrangement and the diagram Fig. 3 is merely given as one instance of a circuit in which this transformer is adapted for use and consists of the usual loop aerial 21, 15 variable condenser 22, potentiometer 23, the telephone receivers 24, the lamps or bulbs 25 and 26, and the usual connections with the batteries A and B.

My transformer is indicated diagrammatically at 27, the primary coil being connected on one side with the plate of the first bulb and the receiver and battery on the other side, while the secondary is connected with the loop on one side and grid of the second 25 bulb on the other side. This secondary current is therefore an amplification of the current passing through the primary and this is again amplified in passing through the bulb 26 to the receiver.

30 The principal features of the invention, as are hereinafter set forth in the claims, are involved in the construction of the transformer with a movable core to vary the inductance of the circuit for the purpose of 35 tuning. A further feature resides in providing the iron of the transformer in finely divided form, either the elongated type of Fig. 1 or the dust like type of Fig. 4. In Fig. 1 the particles are in the form of flat 40 strips of the thinness of about two thousandths of an inch and in either arrangement the iron is practically uniformly distributed throughout the area of the core so that the area of the iron at any point of cross section 45 is uniform with that at any other point.

Having thus fully described my invention, what I claim and desire to secure by Letters Patent of the United States is—

1. In a radio frequency transformer, a

cylindrical shell of non-magnetic material, 50 a second shell of similar material supported therewithin, the axes of the shells coinciding, a secondary coil formed of two coiled parts in spaced relation on said second shell, a primary coil positioned between the two coils 55 of the secondary, an iron core movable longitudinally of the secondary shell, said core comprising a non-magnetic shell and mass of iron in finely divided state therewithin, and means for adjusting the core longitudinally 60 of the axis of the coils.

2. In a radio frequency transformer, a cylindrical shell of non-magnetic material, a second shell of similar material supported therewithin, the axes of the shells coinciding, a secondary coil consisting of two coil parts in spaced relation on the second shell, a primary coil positioned centrally between the secondary coils on the second shell, an iron core in the second shell consisting of a 70 mass of iron in finely divided state, a stem of non-magnetic material for the core extending through one end of the outer shell, spring means engaging the stem, the core and stem being movable on the axis of the 75 two shells and held in adjusted position by the spring, a removable closure member for the outer shell, and terminals for both the primary and secondary coils secured to the 80 said closure member.

3. In a radio frequency transformer, a shell of non-magnetic material on which the secondary coil is wound in a plurality of spaced coiled parts, a primary coil wound on the shell in a position intermediate the secondary coil parts with substantially equal portions of the secondary coil on opposite sides of the primary coil, an iron core in the second shell consisting of a mass of iron in non-homogeneous form, the area of iron at 85 any point of cross section being practically uniform with that at any other point, and means for adjustably positioning the iron core relative to the coils.

In testimony whereof, I sign this specification. 90

ROBERT L. OSBORNE.
